The ornamental design for a food container, as shown and described.

DESCRIPTION

FIG. 1 is a front perspective view of a food container showing our new design;

FIG. 2 is a front elevation view thereof;

FIG. 3 is a back elevation view thereof;

FIG. 4 is a top plan view thereof; and,

FIG. 5 is a bottom plan view thereof.

It should be understood that the labels used herein for describing orientation (e.g., front, back, top, bottom, right, and left) are merely for reference, and the embodiments of our design may be disposed in any manner and still be within the scope of the present invention. It should also be understood that the elements of the right elevation view, left elevation view, front elevation view and back elevation view of the embodiment of FIGS. 1-5, are identical. As such, only the front elevation view and the back elevation view are shown.

The broken lines in the drawings depict portions of the food container in which the design is embodied that form no part of the claimed design.
